UNITED STATES PATENT OFFICE

WILHELM HECKEL, OF HAMBORN, GERMANY, ASSIGNOR, BY MESNE ASSIGNMENTS, TO
C. H. ELLSWORTH

PROCESS FOR TREATING COAL AND LIKE SUBSTANCES

No Drawing.

Application filed August 30, 1921. Serial No. 496,973.

My invention relates to the treatment of substances such as coal, which evolve hydrocarbons when heated and which may be included under the term of "bitumen-bearing substances", this term being given a broad interpretation. The object of my invention is to obtain a high yield of valuable products from substances of the character indicated. I have found that the relatively high temperatures employed hitherto in the treatment of coal, and the like for the production of gas for industrial uses are destructive of certain hydrocarbons, particularly methane and heavy liquid hydrocarbons, which become decomposed or polymerized at such high temperatures. I have further ascertained that by restricting the heat to which the gas will be subjected at any stage after evolution from the coal or other bitumen-bearing substance to a relatively low temperature (for instance about 500° C.), such objectionable decomposition or polymerization is avoided, the heavy hydrocarbons are obtained in their original condition instead of becoming wholly or largely converted into "coke-oven tar", and additional advantages are secured with respect to the solid and to the non-condensable gaseous products (i. e. gaseous products non-condensable at atmospheric temperature, as one skilled in the art will readily understand) which also result from the treatment. The heavy hydrocarbons, particularly of the aliphatic series, and light oils of the aliphatic series, which my treatment yields, have valuable properties as lubricants.

Briefly stated, my invention consists in subjecting the bitumen-bearing substances to a temperature not exceeding a maximum of about 500° C., that is to say, a temperature below the decomposition and polymerization point of the hydrocarbons originally evolved from such substances. The treatment may be carried out while the material is stationary or practically so, for instance, in upright retorts or furnaces of well known types, but preferably the material is kept in motion during the heating, and rotary kilns of certain existing types are available for this purpose. Inasmuch as usual appara-

tus may be employed for my process, I have deemed it unnecessary to furnish a drawing of such apparatus. The treatment may be carried out continuously or intermittently.

The result of the treatment is the production of a solid, a type of coke (low-temperature coke) which has considerable heating value, and which may be utilized for any of the purposes for which coke is adapted, such as heating, the making of producer gas or of water gas, etc. Another part of the products is obtained (after condensation) in liquid form, this portion being a mixture of tar, oils and pitch. This liquid or condensable portion (i. e. the portion condensable at or above atmospheric temperatures, as one skilled in the art will readily understand) is rich in hydrocarbons of the aliphatic series (i. e. in members of the broad group of liquid hydrocarbons), also in oils of the aliphatic series (i. e. in liquid hydrocarbons, particularly in those having lubricating properties), but free from naphthalene, and the pitch residue is poor in hydrocarbons (i. e. the pitch is relatively devoid of free hydrocarbons per se or, in other words, hydrocarbons in a non-polymerized or fixed state are not present in the pitch). As the material is being heated, the bituminous matter contained therein is melted, the liquid hydrocarbons contained in the material are vaporized, while the hydrocarbons contained in the material as gases are liberated in that form. The condensable vapors (i. e. the portion condensable at or above atmospheric temperatures, as one skilled in the art will readily understand) are treated in any suitable manner (as by a well known cooling operation, preferably in successive stages with a separation of some products at the end of each stage) to obtain therefrom the liquid products desired, particularly the tar, the aliphatic hydrocarbons and the aliphatic oils.

The gaseous portion of the products (which consists chiefly or entirely of gases non-condensable at atmospheric temperatures) may receive the usual cleaning or washing treatments. This gas is rich in hydrocarbons of the ethylene and paraffine

series, but contains very little hydrogen, or even none at all. The gas obtained, therefore, is of considerable heating value, being far superior in this respect to ordinary producer gas.

My process, therefore, yields three products or classes of products, viz; first, a solid or substantially solid residue which I term low-temperature coke; second, a mixture of 10 a special tar (low-temperature tar), heavy hydrocarbons and oils, which have valuable lubricating properties; third, a gas of high heating value.

The temperature of the gases or other medium employed for heating the bitumen-bearing substances may be considerably above 500° C. (for instance 900° C.), but it is important that these substances themselves should not reach a temperature above 20 the decomposition and polymerization point of the hydrocarbons originally contained in said substances. Only low-temperature tar, that is to say, tar produced at temperatures not exceeding a maximum of about 500° C. 25 contains the hydrocarbons in the same chemical condition in which they occur in the coal or other bitumen-bearing substance (i. e. the chemical structure of the hydrocarbons are substantially unchanged by the low temperature heat treatment or, in other words, compounds in the form of aliphatic compounds in the coal would not be converted in ring compounds by distillation and vice versa), and in which such hydrocarbons have 30 specific useful properties similar to those of petroleum and its products. If the tar-containing gases are subjected to materially higher temperatures, the resulting tar will not be the valuable low temperature tar, but 35 40 a lower grade tar of the same character as coke-oven tar. The gases and vapors which, at the time of their separation from the solid product, may have a temperature of about 420° C. may be further treated, for instance, 45 by washing and cooling in three stages, as to 130° C. in the first stage, to 65° C. in the second, and to 35° C. in the third, to separate the tar (by the first two stages) and the oil (by the third stage).

50 When in the claim the term "coal" is used, it is intended to include equivalent bitumen-bearing substances of a solid nature.

I claim:

The process of thermally treating coal to 55 produce a plurality of products, including coke, low temperature tar relatively free from naphthalene, oils of the aliphatic series having lubricating properties and a gas rich in hydrocarbons of the ethylene and paraffin 60 series which comprises subjecting the said substances to a temperature not exceeding approximately 500° C. to cause the distillation of volatile products, continuing the distillation at a temperature not exceeding 500° 65 C. until the substance has received its treat-

ment, withdrawing the volatile products under temperature conditions not higher than 500° C., and progressively cooling the withdrawn volatile products to successive cooling stages of the order of approximately 130° C. 70 in the first stage to cause condensation of one portion of low temperature tar, 65° C. in the second stage to cause condensation of another portion of low temperature tar, and 35° C. in the third stage to cause condensation of liquid hydrocarbons including oils of the aliphatic series having lubricating value and then collecting the volatile products uncondensed at 35° C.

In testimony whereof I have hereunto set 80 my hand.

DR. WILHELM HECKEL.
